**COMBINED TELEPHONE MOUTHPIECE
STERILIZER AND PERFUMER**

Michiko Onuki, 688 Nishiya-cho, Hodogaya-ku,
Yokohama, Japan

Filed Nov. 13, 1968, Ser. No. 14,436

Term of patent 14 years

Int. Cl. D14—03; D23—99

U.S. Cl. D26—14

FIG.1

FIG.2

FIG.3

FIG.4

FIG.5

FIG.6

FIG. 1 is a top plan view of a combined telephone mouthpiece sterilizer and perfumer embodying my new design;

FIG. 2 is a side elevation thereof;

FIG. 3 is a section taken on lines III—III of FIG. 1;

FIG. 4 is a top perspective view of the combined telephone mouthpiece and perfumer;

FIG. 5 is a bottom perspective thereof; and

FIG. 6 is a perspective view of the combined telephone mouthpiece and perfumer on a telephone handset.

The broken line representation of the telephone handset is shown for illustrative purposes only.

The characteristic features of my design for a combined telephone mouthpiece sterilizer and perfumer, resides in the specific configuration of the top mouthpiece

element, as best illustrated in FIGS. 1, 4 and 6 on the drawing.

I claim:

The ornamental design for a combined telephone mouthpiece sterilizer and perfumer, as shown and described.
